UNITED STATES PATENT OFFICE.

JOHN BUSHKOVSKI, OF THE AMERICAN EXPEDITIONARY FORCES.

PICTURE-FRAME.

1,308,695.

Specification of Letters Patent.

Patented July 1, 1919.

Application filed September 11, 1918. Serial No. 253,598.

To all whom it may concern:

Be it known that I, JOHN BUSHKOVSKI, a citizen of the United States, and a member of the American Expeditionary Forces, have invented new and useful Improvements in Picture-Frames, of which the following is a specification.

This invention relates to picture frames and the principal object of the invention is 10 to provide means whereby the main part of the frame will be hidden by the picture.

Another object of the invention is to make the frame adjustable so that it may be made to fit pictures of different sizes.

15 Another object of the invention is to provide a device of this character which is simple and durable in construction, reliable and efficient in operation and one which can be manufactured and placed upon the market 20 at a minimum cost.

The invention also consists in certain other features of construction and in the combination and arrangement of the several parts, to be hereinafter fully described, 25 illustrated in the accompanying drawings and specifically pointed out in the appended claims.

In describing my invention in detail, reference will be had to the accompanying 30 drawings wherein like characters denote like or corresponding parts throughout the several views, and in which:—

Figure 1 is a front view of the invention with parts omitted and one of the securing 35 means in inoperative position.

Fig. 2 is a longitudinal sectional view through one of the sides of the frame.

Fig. 3 is the section on the line 3—3 of Fig. 1.

40 Fig. 4 is a section on the line 4—4 of Fig. 1.

Fig. 5 is a view of the frame with the picture and glass plate in position.

Fig. 6 is a view of the rear of the frame.

45 As shown in these views, the frame consists of a plurality of angle members 1 and 2 which are telescopically connected with each other to enable the frame to be adjusted to accommodate pictures of different sizes. As shown the sections 1 have their ends engaging in the sections 2. I prefer to form the sections of tubular formation with their front faces flattened as at 3. The ends of the sections 1 are pointed as at 4

50 to facilitate their entrance into the sections 2. I prefer to make the frame of metal,

though of course, it will be understood that it may be made of any suitable material. The sections 2 are provided with thickened portions 5 on their rear faces which are provided with screw threaded holes to receive clamping screws 6. These screws engage the sections 1 to clamp said sections together. 60

Each limb of the sections 2 is provided with a projection 7 at the side thereof which 65 is provided with a screw threaded hole to receive the screw 8 which holds a spring plate 9 in position on said projection. I prefer to make this spring plate in the form of a leaf. Each plate is adapted to be swung 70 on the screw 8 so that it may be moved into the position shown in full lines at the bottom of the frame in Fig. 1 to permit the placing of the picture and the covering glass on the flat part of the frame sections. After 75 the glass and picture are placed in position the spring plates are swung over the same so that they will hold the picture and glass on the frame by spring tension. The spring plates are curved as shown in Fig. 3 to provide a flattened part 10 to engage the glass. The picture and glass are also clamped in position by means of the clamping screws 11 placed at the corners of the frame and provided with a swiveled base 12 made of rubber or other suitable material. These screws are carried by a bracket 13 secured to or formed with the sections at the corners thereof. These brackets are of angular form so as to form a recess for receiving the 80 corners of the picture and glass. I prefer to cover the set screws by means of an ornamental plate 14, shown as being in the form of a leaf, which is carried by a spring clip 15 of hooked form and adapted to engage 85 the sections of the frame adjacent the corners thereof as clearly shown in Figs. 1 and 4.

It will thus be seen that all parts of the frame excepting the ornamental plates 9 and 100 14 are entirely covered by the picture. It will also be seen that the frame may be adjusted to fit pictures of different sizes.

It is thought from the foregoing description that the advantages and novel features 105 of my invention will be readily apparent.

I desire it to be understood that I may make changes in the construction and in the combination and arrangement of the several parts, provided that such changes fall within 110 the scope of the appended claims.

Having described my invention what I

claim and desire to secure by Letters-Patent is:

1. A picture frame comprising a plurality of adjustable sections having flattened front faces to receive the picture, outwardly extending brackets on the outer edges of said frame, rotatably mounted spring plates on said brackets and clamping means at the corners of the frame.

2. A picture frame having its front face flattened to receive the picture, corner brackets of angular shape extending upwardly from the outer edges of the frame, clamping screws carried by the brackets, an ornamental plate, and a spring hook carrying the same for covering the corner brackets.

In testimony whereof I affix my signature.

JOHN BUSHKOVSKI.

Copies of this patent may be obtained for five cents each, by addressing the "Commissioner of Patents, Washington, D. C."
